UNITED STATES PATENT OFFICE.

OSCAR LOVELAND, OF ADAMS, NEW YORK.

HAY-CARRIER.

SPECIFICATION forming part of Letters Patent No. 284,069, dated September 11, 1883.

Application filed March 24, 1883. (No model.)

To all whom it may concern:

Be it known that I, OSCAR LOVELAND, a citizen of the United States of America, residing at Adams, in the county of Jefferson and State of New York, have invented certain new and useful Improvements in Hay-Carriers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to transferring hay and sheaf-grain from wagons to the hay-mow or grain-bins of a barn, its object being to enable wagons to be rapidly unloaded with a comparatively small amount of labor.

20 The improvement consists in certain novel constructions and combinations of devices composing an unloading apparatus, which will be hereinafter particularly described in connection with the accompanying drawings, and 25 its novel features definitely pointed out in the appended claims.

In the drawings, Figure 1 is a side view of an unloading apparatus constructed according to my invention. Fig. 2 is a section on the 30 line $\alpha\alpha$ of Fig. 1. Fig. 3 is a plan view of the sling. Fig. 4 is a detached perspective view of one of the sling-clutches with the parts arranged as about to separate.

The letter A indicates a track or rail, provided with suspending rods and hooks a, by 35 which it may be suspended from the rafters or other suitable supports in a barn. Upon this track travels a depending carriage, B, composed of hangers c c c c, arranged in two pairs, secured at the ends and on opposite sides 40 of a connecting-bar, d. The upper ends of the hangers c extend above the rail, and each has to its inner side pivoted a wheel, e, which runs upon the upper side of said rail. At one end 45 of the carriage both of the two hangers at that end have pivoted to the inner sides of their lower ends pulleys f f', and at their other end one of the hangers only has pivoted to the inner side of its lower end a pulley, f'.

50 To the under side of the rail A is secured a lug or catch, g, and to the upper side of the

bar d of the carriage is secured a spring-latch provided with a notch to engage said catch. In a slot formed in the rail A is pivoted a tripping-lever, i, which is provided at its lower end with projections i', which extend through the rail on opposite sides of the catch g, and either of these projections may be forced against the latch to throw it out of engagement with said catch by swinging the trip-lever on its pivot. The latch is beveled on both sides of its notch, so that in whichever direction the carriage may travel the latch will be struck and forced downward by the catch g until the notch reaches a position to engage 65 with said catch.

To one side of the bar d is pivoted a stop-lever, k, the end of the long arm of which is arranged to rest upon the periphery of the pulley f, or upon the cord which passes over 70 said pulley when the lever is free, and the upper end of said lever is bent to form a short arm, k', which will be struck by the catch g and pressed downward, so that the lower end of the lever k will be lifted clear of the pulley 75 f and its cord.

L indicate two double pulley-blocks, provided with hooks l, which are to be attached to the opposite ends of a sling, M, as shown in Fig. 1.

N designates a rope, which has one end secured to the end of the carriage B adjacent to the pulley f, and passes downward through both of the blocks L L, then upward over pulley f, thence over pulley f', again downward 85 through the blocks L L, and thence over pulley f, and off to a stationary pulley, which may be located at any convenient point.

Referring to Fig. 3, the sling M is composed of two parts, m m', connected by clutches p p. 90 Each half of the sling in the present instance is composed of two cross-bars, q, and four ropes passing through said bars, the outer ends of the four ropes of each part being secured to rings r, but the inner ends of the ropes being connected 95 in pairs to the clutches, respectively. Each clutch is composed of two parts, the first consisting of a block, s, having two slots, s' and s''. In the slot s' is pivoted a lever, s', which has projecting from one side a lug, s', which is arranged 100 to partially close the slot s'' when the lever s' lies longitudinally in its slot, but will be raised or

turned back to open said slot s^2 when the lever s^3 stands transversely. The block s is provided with bail s^5 , by which it may be attached to the ropes. The other part of the clutch 5 consists of a tongue or catch piece, s^6 , having one end provided with an eye for attachment to the ropes, and its other end provided with a lateral projection, which is adapted to catch over and engage with the lug s^4 of the lever s^3 10 when the end of the tongue is inserted through the slot s^2 , as shown in Fig. 3. These tongues s^6 are attached to the looped ends of the ropes of the part m' of the sling, and the other parts of the clutches are attached to the ropes of the 15 other part, m , of the same. To the long arms of the levers s^3 are attached cords t , by which said levers may be thrown to a transverse position when it is desired to disengage the tongues and allow the two parts of the sling 20 to separate.

The operation of my unloading apparatus as now described is as follows: The carriage B is run to such position that its spring-latch h will engage with the lug g on the rail, and at this 25 time said lug strikes the upper end of the lever k and lifts its lower end clear of the pulley f . The carriage being thus held stationary, the loaded wagon is driven under the same and a quantity of hay or sheaf-grain is placed upon 30 the sling, the two parts of which are clutched together. The rope N is then slackened up to lower the double pulley-blocks L L , and these blocks are hooked to the opposite ends of the sling, which, with its load, may be then raised 35 clear of the wagon by pulling on the free end of the rope N . The trip-lever i being then swung to one side by means of a cord attached thereto, the latch h will be disengaged from the lug g , and the carriage may then be started to 40 travel on the rail to carry its load to where it is to be deposited. Immediately the carriage leaves its original position the lever k becomes released from the lug g , and the lower end of said lever falls upon the rope, passing over the 45 pulley f , and binds said rope to prevent its running back over the pulley. When the carriage reaches the point where the grain is to be deposited, the cords t are pulled to turn the levers s^3 of the clutches and permit the two

parts of the sling to separate and drop the 50 load of grain. The carriage may then be run back and reloaded the same as before.

Having now fully described my invention and explained the operation thereof, I claim—

1. The combination, with the rail A, having 55 lug g , and depending carriage B, arranged to travel on said rail, and provided with the pulleys f , f' , and f'' , of the spring-latch h , arranged to engage said lug, and the lever k , having its lower end arranged to rest upon the pulley f , 60 and its upper end arranged to be pressed downward by the lug g at the same time that said lug engages the spring-latch, substantially as described.

2. The combination, with the rail A, the de- 65 pending carriage arranged to travel on said rail, and the pulleys, cords, and pulley-blocks connected with said carriage, as described, of the sling composed of two parts, connected with said pulley-blocks, respectively, and connected together by detachable clutches, essen- 70 tially as set forth.

3. The combination, with the sling composed of two parts, m m' , of the clutches, each composed of two parts, which are attached to the 75 parts of the sling, respectively, each clutch being composed of the slotted block-lever s^3 and attached lugs s^4 , and the tongue s^6 , adapted to engage said lug, substantially as described.

4. The herein-described unloading appa- 80 ratus, composed of the rail A, provided with the lug g and tripping-lever i , the depending carriage B, arranged to travel on said rail, and provided with the spring-latch h , pulleys f , f' , and f'' , and the lever k , the double pulley- 85 blocks L L , the cord N , the sling composed of two parts connected with said pulley-blocks, respectively, and the clutches arranged to connect and disconnect the two parts of said sling, the whole being constructed and arranged to 90 operate as specified.

In testimony whereof I affix my signature in presence of two witnesses.

OSCAR LOVELAND.
